DESIGN FOR AN ELECTRON DISCHARGE TUBE

William W. Eitel, and Jack McCullough, San
Bruno, Calif., assignors to Heintz & Kaufman,
Ltd., San Francisco, Calif., a corporation of
Nevada

Application December 11, 1933, Serial No. 50,040

Term of patent 14 years

To all whom it may concern:

Be it known that we, WILLIAM W. EITEL and
JACK McCULLOUGH, citizens of the United States
of America, and residents of San Bruno, county
of San Mateo, State of California, have invented
a new, original, and ornamental Design for an
Electron Discharge Tube, of which the following
is a specification, reference being had to the ac-
companying drawing, forming part thereof.

The drawing shows a perspective view of the
tube showing our new design.

We claim:

The ornamental design for an electron dis-
charge tube, substantially as shown.

In testimony whereof, we have hereunto set our
hands.

WILLIAM W. EITEL.
JACK McCULLOUGH.
